UNITED STATES PATENT OFFICE.

ARTHUR C. EASTWOOD, OF CLEVELAND, OHIO.

LIFTING-MAGNET.

1,015,728.

Specification of Letters Patent. Patented Jan. 23, 1912.

Application filed May 13, 1910. Serial No. 561,096.

To all whom it may concern:

Be it known that I, ARTHUR C. EASTWOOD, a citizen of the United States, residing at Cleveland, in the county of Cuyahoga and State of Ohio, have invented new and useful Improvements in Lifting-Magnets, of which the following is a specification.

My invention relates to electro-magnets and has special reference to electro-magnets designed for lifting and transporting magnetic materials and known as lifting magnets. Its object is so to construct the magnets that they are normally sealed against the entrance of moisture and that they automatically permit the escape of any gases or vapors generated in the magnet case. In the specification accompanying Letters Patent, No. 950,718, granted to me March 1, 1910, I set forth in some detail the manner in which moisture obtains access to the interior of lifting magnets, and described a means by which moisture may be excluded from the magnets and at the same time permit the heat-softened insulating material to expand freely. The present invention provides novel means for accomplishing the same results.

Electromagnets of the kind to which my invention applies are known as lifting magnets, and in service are suspended from the hook of a crane or other hoisting device and used for attracting and transporting magnetic material, the material being released from the magnet by opening the circuit of its magnetizing winding. With lifting magnets of large size the circuit of the winding is very highly inductive and a high induced voltage occurs when the circuit of the magnet is opened, and as this occurs at very frequent intervals, often as frequently as four times a minute, during the operation of the magnet, the insulation of the magnet is subjected to very frequent and severe electrical stresses. Further than this, such magnets are commonly used out of doors under all kinds of weather conditions, and are subjected to a great amount of shock and abrasion when dropped upon piles of material to be handled or swung against piles of such material, cars, or other obstructions.

In order to keep the weight of the lifting magnet at a reasonable value, compared with the weight of material which the magnet will lift, it is necessary to make the winding as compact as possible. This ne-

cessitates a high current density in the winding and the dissipation of a large amount of heat from a restricted surface. In commercial lifting magnets of large size it is not uncommon to dissipate as much as 15000 watts as heat while the magnet is in operation. In consequence of the high current density and large amount of heat to be dissipated, the windings of such commercial lifting magnets are of necessity worked at temperatures very much higher than that ordinarily used in other electrical windings. It is not uncommon for a winding of such a lifting magnet to reach a temperature of five to six hundred degrees Fahr., and occasionally a temperature of 800 degrees may be reached. Up to the present time it has not been possible to find insulating materials which are altogether inert at such temperatures, as there will invariably be gases and vapors liberated from the material before this temperature is reached. If means are not provided for the escape of these gases and vapors, pressure will be set up in the magnet case, which will eventually force an escape. My invention affords a simple and reliable means for permitting of the escape of such gases and vapors, at the same time automatically sealing the magnet case when the temperature of the magnet has been suitably reduced.

Referring to the accompanying drawing, Figure 1 is a perspective of a lifting magnet containing my invention, and Fig. 2 is an enlarged section of Fig. 1 taken on the line II-II.

The magnet shown on the drawings has a great many of the features of the magnet shown on the drawings which form a part of Letters Patent, No. 928,510 granted to me July 20, 1909, and to such parts of the magnets shown on the drawings of this application as are substantially the same in structure or function as corresponding parts shown on the drawings of this patent, I shall assign the same reference characters in order to facilitate a more ready understanding of the structure shown on the drawing of this application, but the precise structure shown is not essential to the present invention, as will be presently understood.

On the drawing A is an annular bottom plate preferably of brass provided with the inner and outer flanges α' and α'' secured by screws to the lower face of the annular outer pole B and the inner pole C of the

magnet case or frame. The plate A is provided with the upwardly-projecting flange a^4 serving as a mandrel, upon which the coils e^1 , e^2 , e^3 , and e^4 are wound. The coil e^1 rests on the insulating plate a^5 which is seated on the plate A. The insulating plate a^7 is placed above the coil e^1 and the second coil e^2 is wound so as to rest on the plate a^7 . The coils e^3 and e^4 are placed above the coil e^2 in a similar manner with insulating plates a^8 between adjacent coils and above the top coil e^4 . The coils are connected together in any desired manner, not shown, to cause the current to flow in series through the same.

Radial straps (only one, s' , being shown) are placed over the top plate a^8 and are drawn down thereon by means of the screws or bolts d' and d^2 (only one of each shown), the screws d' engaging in bosses at the upper end of the flange a^4 and the bolts d^2 passing through suitable holes near the edge of the plate A. By these means the entire winding containing several sections is firmly bound to the bottom plate A. The winding is afterward impregnated with an insulating compound which will thoroughly waterproof it.

The winding with all the parts assembled and clamped as hereinbefore described becomes a unit which may be moved about and assembled in the magnet case or frame, without danger of injury to the same. This unit is placed within the magnet frame and secured thereto by screws as shown in dotted lines; Fig. 2. The walls of the magnet case are provided with pockets s^{10} to accommodate the clamping means and bolts, which engage the ends of these straps. The outer wearing plate D which I preferably make of manganese steel is then put in place and the pole shoe c' secured to the outer face of the outer pole C by means of the bolts c^8 . The central pole shoe C' is then secured to the face of the central pole B by means of the bolts b^7 . The terminals of the winding are brought up through opening g^{12} and the insulating plate g^2 and connected in the recess g^{13} above the plate g^2 to the cable g^6 leading to the supply lines for energizing the magnet, but before the plate g^2 is put in place, a hot insulating sealing compound which hardens when cooled and softens when heated, is poured into the frame through the recesses g^{12} and g^{13} . In order to completely fill the space between the unit winding and the magnet frame with this compound, I admit current to the winding and preferably apply heat externally to the magnet frame and bring the temperature of the magnet substantially to as high a temperature as it will reach in actual practice. This causes the parts to expand and all moisture to be expelled. I then pour in the said hot insulating com-

pound which thoroughly fills the vacant space within the frame and around the unit winding. As the magnet and the compound cool and contract, I supply more of the insulating compound so that when the magnet is cool, the space between the unit winding and the magnet frame is entirely filled with the compound. The compound is made to fill the recess g^{12} and the plate g^2 is then secured above the recess by screws. The said insulating compound is designated by the letter i .

The recess g^{13} is provided with the insulating compound which covers the cable and winding terminals. This recess is provided with the cover g^8 bolted to the magnet frame. To this cover g^8 , I hinge the cover g^{14} which drops down into the recess g^{15} provided for the cable g^6 , the cover having the slot g^{16} for the said cable.

I provide a number of ducts or vents v around the magnet, the vents leading preferably from the outer pockets s^{10} outwardly and downwardly through the wall of the magnet frame and terminating between adjacent ribs r . The vents v allow the air to escape from the space between the unit winding and the magnet casing when the insulating and sealing compound is poured in, and permits the compound to entirely fill the said space. Some of the compound will finally run out through the vents. When the magnet cools, the compound in the vents will harden and seal them against the entrance of moisture.

If the magnet should be connected to the source of current supply for a longer period than it was designed to operate, such as being left energized all day or all night, or should be subjected to an abnormally high voltage, or by any accidental cause the temperature of the magnet should become higher than when the compound was put in, the vents v act as safety valves and allow some of the heated softened insulating compound and any vapors or gases formed within the magnet to escape. If these vents be not provided, the pressure within the magnet may become great enough to cause the compound to burst out through the recess g^{12} or through the joint between the plate A and the magnet poles of the magnet. The vents v open downwardly so that rain or moisture cannot enter.

It is now clear that my invention is not confined to any particular type of coil or coils or of unit winding or even to the presence of a unit winding. Accordingly I have not described the unit winding and some of the other parts of the magnet in all details.

I claim—

1. A lifting magnet, comprising a frame, a magnetizing winding therein, there being vents leading from the space in which the winding is seated through the frame, and

a heat-softening insulating and sealing material in the said vents and the space between the frame and the winding, whereby when the temperature of the compound exceeds a predetermined value a portion of the same with any vapors and gas in the said space may escape and when the temperature declines to the said value the said material will serve to seal the vents against the entrance of moisture.

2. A lifting magnet, comprising a frame, a magnetizing winding therein, there being outwardly and downwardly inclined vents leading from the space in which the winding is seated through the frame, and a heat-softening insulating and sealing material

in the said vents and the space between the frame and the winding, whereby when the temperature of the compound exceeds a predetermined value a portion of the same with any vapors and gas in the said space may escape and when the temperature declines to the said value the said material will harden in the vents and seal the same against the entrance of moisture.

Signed at Cleveland, Ohio, this 11th day of May, 1910.

ARTHUR C. EASTWOOD.
